UNITED STATES PATENT OFFICE.

LESLIE DANA, OF ST. LOUIS, MISSOURI, ASSIGNOR TO CHARTER OAK STOVE & RANGE COMPANY, A CORPORATION OF MISSOURI.

DESIGN FOR A DOMESTIC RANGE.

Application filed January 9, 1928. Serial No. 24,782. Term of patent 14 years.

To all whom it may concern:

Be it known that I, LESLIE DANA, a citizen of the United States, residing in the city of St. Louis, State of Missouri, have invented a new, original, and ornamental Design for Domestic Ranges, of which the following is a specification, reference being had to the accompanying drawing, forming a part thereof.

The figure is a perspective view of the domestic range, showing my new design.

I claim:

The ornamental design for a domestic range, as shown.

LESLIE DANA.
